UNITED STATES PATENT OFFICE.

JOSEPH M. CRUCET, OF NEW YORK, N. Y.

DESIGN FOR AN ELECTRIC-LAMP SHADE.

Application filed December 5, 1921. Serial No. 520,167. Term of patent 3½ years.

To all whom it may concern:

Be it known that I, JOSEPH M. CRUCET, a citizen of the United States, and a resident of the city, county, and State of New York, have invented a new, original, and ornamental Design for an Electric-Lamp Shade, of which the following is a specification, reference being had to the accompanying drawings, forming part thereof.

The drawing is a perspective view of a lamp shade showing the improved design.

I claim:

The ornamental design for an electric lamp shade as shown.

JOSEPH M. CRUCET.
